FLYING MACHINE

William K. M. Bartsch, Kansas City, Mo.

Application November 22, 1943, Serial No. 511,277

1 Claim. (Cl. 244—20)

My invention relates to improvements in flying machines, of a type similar to the ornithopter, excepting that in my machine the propeller blades revolve continuously in one direction around their axes.

One object of my invention is the provision of a flying machine of the kind described, and of novel construction, in which the propeller blades are so arranged and operated as to lift and carry the machine forwardly, and which can be flown without the use of wings.

A further object of my invention is the provision of a novel flying machine, which is very simple, of relatively few parts, which has stability, is easily operated, is durable, and which is efficient in its operation.

Another object of my invention is the provision of a novel propeller blade and of novel means of operating it by which the blade exerts a maximum of lifting and driving effect with a minimum of resistance to its revolution and to the progress of the machine during that portion of its revolution when it is not employed for lifting and driving.

The novel features of my invention are hereinafter fully described and claimed.

In the accompanying drawings, which illustrate the preferred embodiment of my invention,

Fig. 1 is a plan view of the machine provided with wings, shown partly broken away.

Fig. 2 is a front elevation of what is shown in Fig. 1.

Fig. 3 is an enlarged side view of one of the propeller blades, with its crank shaft shown in solid lines, as when the blade is used at one side of the machine and revolves in one direction, the crank shown in dotted lines, being employed when the blade is at the other side of the machine and revolves in the opposite direction.

Fig. 4 is a side edge view of what is shown in Fig. 3.

Fig. 5 is a side elevation of the machine, showing the blades in the vertical plane.

Fig. 6 is a rear elevation of the right hand cam and one of the propeller blades cooperating therewith, and shown in the two horizontal and two vertical positions.

Fig. 7 is a section on the line 1—1 of Fig. 6. Similar characters of reference designate similar parts in the different views.

1 designates the fuselage of the machine having in its upper side an opening 2 for receiving therethrough the operator.

3 designates the front landing wheels, and 4 the axle therefor mounted on the under side of the fuselage. 5 designates the usual rear land-

ing wheel. The fuselage has the usual stern steering mechanism. 6 designates two usual side wings, their end portions being broken away, and which, if desired, may be dispensed with, as the machine has a novel arrangement of propeller blades adapted for lifting, sustaining and forwardly propelling the machine.

Over the wings 6 respectively are two explosive engines 7 and 8 disposed respectively at the right and left sides of the longitudinal vertical plane of the center of gravity of the machine, which plane is designated by A—B and is also the plane of the longitudinal vertical center of the fuselage.

15 Supporting means for the engines 7 and 8 comprise two bars 9 the upper ends of which are respectively fastened to the under sides and forward portions of the engines and which incline forwardly and downwardly to and are fastened, 20 as by welding, to the upper side and middle front portion of the fuselage 1; two bars 10 fastened at their upper ends to the engines 7 and 8 and incline rearwardly and downwardly to and are fastened to the upper side of the fuselage 1; and 25 a horizontal transverse bar 11 fastened at its ends respectively to the engine bodies 7 and 8.

Two driving members comprising two rotary shafts 12 and 13 of the engines 7 and 8 are respectively rotatable in two bearings 14 and 15 30 provided at the rear ends of the engines 7 and 8.

The driving members or shafts 12 and 13 are substantially horizontal, when the machine is on an even keel, and extend forwardly and rearwardly with their axes converging forwardly to 35 ward each other.

Respectively fastened to the rear ends of the driving members or shafts 12 and 13 are two V shaped hubs 16 and 17, which revolve with the shafts 12 and 13, said shafts being revolved by 40 the motors of the engines in opposite directions. The engines 7 and 8 may be of usual explosive type, each having oppositely disposed cylinders.

Respectively pivoted on radial axes in the arms of the hub 16 are two radial propeller blades 18 which revolve with the hub 16 and shaft 12 clockwise, as viewed from the rear. The blades 18 are alike, one being shown enlarged in Figs. 3 and 4, in solid lines. They are disposed diametrically opposite to each other at opposite sides of the 50 axis of the shaft 12. As shown in Fig. 1, the radial axes of the blades 18 diverge rearwardly from each other at an angle of approximately 126 degrees, each radial axis converging forwardly toward the axis of the driving shaft 12 at approximately 63 degrees, said axis of the shaft 12 converging forwardly at approximately 63 degrees.

Each blade 18 has at its inner end a radial shaft 19 having a crank arm 20, the radial shaft 19 being pivoted in one arm of the hub 16, Figs. 3 and 4.

In Fig. 3, the line E—F designates the radial axis of the blade 18. The blade at one side of the axis E—F is wider than at the other side, the longitudinal edge of the narrow side of the blade always being the leading edge, in the revolution of the blade.

The assemblage of the blades 18 is such that when each blade reaches the upper vertical position, shown in Fig. 6, its crank arm 20 will be engaged by an arcuate cam 21 mounted on the bearing 14, so as to swing the blade on its radial axis to a position in which one side of the blade will be in front of and leading the other side. This position is herein termed the side leading position.

As shown in Fig. 1, the cam 21 is transverse to and inclined rearwardly relatively to the axis of the driving member 12, so that as the blade revolves downwardly its angle of incidence will be about 45 degrees, as shown in Fig. 7, when the blade 18 reaches the right hand horizontal position, shown in Figs. 1 and 6. At this time, the blade will be in a vertical plane at right angles to the longitudinal plane A—B, preferably with its radial axis in the vertical transverse plane C—D, Fig. 1, of the center of gravity of the machine.

The arc of the cam 21 is of such length that when the blade 18 in its downward movement of revolution reaches the lower vertical position shown in Fig. 6, the crank arm 20 of the blade will leave the cam 21, and the blade will be permitted to swing freely on its radial axis, and, due to the pressure of the air, in the upward revolution of the blade, the blade will swing to the edge leading position, shown in Fig. 6 in the lower vertical and left horizontal positions.

Each blade 18 is guided in its downward movement by its crank arm 20 and the adjacent cam 21 from an edge leading position toward a side leading position until it passes the horizontal, the blade, in the horizontally extending position, extending at right angles to the straightahead and inclining upwardly and rearwardly from its front edge at approximately forty five degrees. The blade thus, during its downward movement will exert both a lifting and a forward propelling effect.

By so disposing the blades 18 and having their axes diverging rearwardly from the driving shaft, and having the driving shaft extending forwardly and rearwardly at an angle to the straightahead, as shown, a maximum of driving effect is obtained with a minimum of air resistance by the blades during their upward movement.

Thus the blades 18 in revolving clockwise, viewed from the rear, will consecutively lift and propel the machine forwardly, and by reason of their arrangement, in passing upwardly in their non-resistant position, they will present a minimum of resistance to the forward movement of the machine, and in their downward revolution they will exert a maximum of power directed to lifting and propelling the machine forwardly.

At the other side of the machine, on the hub 17 are pivoted on radial axes two radial propeller blades 18' having each a radial shaft 19' provided with a crank arm 20' which engages a cam 21' mounted on the bearing 15. The blades 18' correspond in structure and mode of operation to the blades 18, excepting that their crank arms 20',

shown in dotted lines in Figs. 3 and 4, are disposed reversely to the crank arms 20, and the blades 18' are positioned reversely to the blades 18 and revolve in opposite directions, or counter-clockwise, as viewed from the rear.

Brace rods 22 connect the outer end portions of the blades 18 and 18' with the hubs 16 and 17, for stabilizing the blades against centrifugal action.

- 10 The driving members or shafts 12 and 13 of the engines 7 and 8 are inclined to the longitudinal axis A—B, so as to bring the blades 18 and 18' into their most efficient positions of revolution, and the convergence of the axes of the driving members 12 and 13 forwardly effects stabilization, as does the revolving them and the blades in opposite directions.

The cam 21' is inclined oppositely to the cam 21 to accommodate it to the revolution of the blades 18' oppositely to the blades 18.

The degree of inclination of the cams 21 and 21' may be varied to suit the angles of incidence desired in the blades when they are revolving downwardly.

- 25 Any usual mechanism may be employed for controlling the operation of the engines 7 and 8, and any usual tail steering assembly may be employed.

The wings 6, as shown, are disposed above the landing wheels 3 and below and clear of the revolving blades 18 and 18' respectively, and are intersected by the vertical transverse plane of the center of gravity C—D, Fig. 1.

The two propelling mechanisms shown and described, with the fuselage and tail steering assembly will form a flying unit, which, in combination with the wings 6, maximum lifting at the start and at landing is effected, and in horizontal flight, maximum push and minimum lift of the blades is obtained.

Various modifications of my invention, within the scope of the appended claim, may be made without departing from the spirit of my invention.

15 What I claim is:

- In combination with the supporting structure of a flying machine, two propelling means disposed respectively at opposite sides of the longitudinal axis of said supporting structure, each of said propelling means comprising as follows: a rotary driving member extending forwardly at an angle acute to said longitudinal axis, supporting means on said supporting structure for said rotary driving member, means for rotating said driving member, a hub on and revolvable with said driving member, a propeller blade pivoted on said hub on an axis diverging from the axis of said driving member so as to swing to an edge leading or to a side leading position and having a crank arm extending laterally from the axis of said blade, and guiding means including a stationary cam on said supporting means by which, when said blade moves downwardly from its uppermost position, its said crank arm will be engaged by said cam so as to swing said blade from an edge leading toward a side leading position until said blade reaches the horizontal position in which position said blade will be inclined from its front edge upwardly and rearwardly, said blade when it has passed the horizontal position a substantial distance in its downward movement having its crank arm released from engagement with said cam so as to be adapted to swing freely on its axis.
